UNITED STATES PATENT OFFICE

GEORGE H. MAGRATH, OF WHITINSVILLE, MASSACHUSETTS

BOBBIN CLUTCH FOR SPINDLES

Application filed July 25, 1928. Serial No. 295,158.

The objects of the present invention are to provide a bobbin clutch which is simple and economical to manufacture and assemble, which is efficient and durable in use, and which is generally superior to previous bobbin clutches of the same general type. The various novel features of construction and functional advantages of this invention will be evident from the following description and appended claims.

For the purposes of illustration one concrete embodiment of the invention is shown in the accompanying drawings, in which

Fig. 1 is a side elevation;
Fig. 2 is a section on line 2—2 of Fig. 1;
Fig. 3 is a section on line 3—3 of Fig. 2;
Fig. 4 is a development of the spring hereinafter described; and

Fig. 5 is a side view of one of the contact pieces actuated by the spring.

The particular embodiment of the invention chosen for the purpose of illustration comprises an ordinary blade 1 and a whirl 2 fixedly mounted on the blade by a pressed fit, the whirl 2 having a hub 3 from which projects a neck 4 and a flange 5 with an annular recess therebetween, which is preferably tapered at the inner end, as shown in Fig. 3. Mounted on the blade 1 in opposition to the hub 3 is a case 6 having four radial slots extending longitudinally from one end throughout the major portion of the length of the case leaving therebetween finger portions 7 which project into the recess between the neck 4 and the flange 5. Disposed in the aforesaid slots are contact pieces 8 having their outer ends hooked to engage inside the case 6, as shown in Fig. 3, and having their inner ends disposed within the annular recess between the neck 4 and the flange 5.

Mounted in the aforesaid annular recess is a spring having a circular base 9 and projecting fingers 10, the base 9 lying between the neck 4 and the inner ends of the fingers 7 and contact pieces 8. This spring, indicated generally by the letter S, is preferably formed from a sheet metal blank (Fig. 4) which is bent into circular form. The normal interior diameter of the spring

base 9 may be somewhat less than the external diameter of the neck 4 so that the spring will yieldingly grip the neck or the spring may be shaped so that the normal exterior diameter of the base 9 is slightly greater than the internal diameter of the case 6 so that when the spring is inserted in the case it expands outwardly against the inner ends of the fingers 7. The spring projections or fingers 10 flare outwardly toward their free ends and engage the contact pieces 8 near their hooked ends, as shown in Fig. 3. The width of the spring projections 10 is preferably equal to or somewhat less than the width of the contact pieces 8; and the opposite side of each contact piece 8 and each slot in case 6 are parallel to each other as shown in Fig. 2. The combined radial thickness of the spring 9 and the case fingers 7 is approximately equal to the width of the annular recess between neck 4 and flange 5 so that when the case 6 is forced into the recess the taper of the recess compresses the fingers 7 against the spring 9 tightly clamping the case and spring in the recess. The thickness of the inner ends of the contact pieces 8 is somewhat less than the thickness of the fingers 7 so that the contact pieces fit loosely in the upper portion of the recess but do fit snugly in the reduced lower end of the recess so that these contact pieces have substantially fixed fulcrum points at their extreme lower ends where these ends seat in the bottom of the recess, as shown in Fig. 3.

In addition to the aforesaid pressed fit of the case 6 and spring S in the annular recess of the hub 3 the case 6 may also have a pressed fit directly with the blade 1 at its outer end, thereby more firmly securing the case in fixed position on the blade. In assembling the parts the whirl 2 is preferably applied to the blade 1 first; and the spring may then be applied either to the neck 4, in which case the internal diameter of the spring base 9 is preferably less than the external diameter of the neck 4, so that the spring clings to the neck, or to the case 6 with the spring fingers 10 projecting into the slots in the case, in which case the ex-

ternal diameter of the spring base is preferably larger than the internal diameter of the case so that the spring clings to the case.

5 After the spring has been applied to the neck or case as aforesaid the case is forced into said annular recess while the contact pieces 8 are held in position on the case also to enter the annular recess.

10 In operation the spring projections 10 press outwardly on the contact pieces 8 holding the outer hooked ends against the case 6 and the inner ends against the flange 5. When a bobbin is applied over the blade 1 and thence over the case 6 until it abuts 15 against the flange 5 the contact pieces are pressed inwardly against the spring action, whereupon the spring fingers 10 yieldingly engage the bobbin through the medium of the contact pieces 8 detachably to hold the 20 bobbin in position.

From the foregoing it will be evident that the spring is held in position by interengagement of the case and the whirl so that the 25 spring need not be applied by a separate pressed-fit operation and it may be made in the form of a split ring from sheet metal without welding or brazing, thereby materially reducing the cost of manufacture and labor of assemblage.

30 Another important feature of the invention consists in the arrangement whereby the spring extends into the whirl thereby affording greater length of spring fingers without necessarily increasing the length of the case

35 6. If the spring were fitted to the blade 1 (instead of the neck 4) in end to end relation to the neck 4, one or the other of two difficulties would be encountered, viz., the spring fingers would be too short and stubby to be 40 efficient or the case 6 and contact pieces 8 would have to be elongated beyond the standard optimum dimensions.

I claim:

45 1. Apparatus of the character described comprising a blade, a whirl mounted on the blade, the whirl having a hub provided with a neck fitting around the blade and an annular recess surrounding the neck, a case mounted on the blade and having spaced 50 fingers extending into said recess, bobbin contact members disposed in the spaces between said fingers and extending into said recess, and a spring having a base secured in said recess between said neck and the 55 inner ends of the fingers and contact members, the spring having projections extending from its base at spaced intervals and bearing against said contact members, the thickness of the inner ends of the contact 60 members being less than the thickness of the fingers so that the contact members fit loosely in said recess.

65 2. Apparatus of the character described comprising a blade, a whirl mounted on the blade, the whirl having a hub provided with

a neck fitting around the blade and an annular recess surrounding the neck, a case mounted on the blade and having spaced fingers extending into said recess, bobbin contact members disposed in the spaces between said fingers and extending into said recess, and a spring having a base secured in said recess between said neck and the inner ends of the fingers and contact members, the spring having projections extending from its base at spaced intervals and bearing against said contact members, the thickness of the inner ends of the contact members being less than the thickness of the fingers so that the contact members fit loosely in said recess, and said spring projections flaring outwardly at their outer ends thereby to urge the contact members outwardly with respect to the case fingers.

70 3. Apparatus of the character described comprising a blade, whirl and casing members mounted thereon and having opposed recesses therein, one of these members having its recess annular in form and spaced from the blade, fingers on the other of these members and extending into the annular recess, a spring comprising a base portion disposed in the annular recess in firm engagement with a plurality of the fingers and with the inner wall of the recess for locking such fingers and the spring from relative circumferential movement, the spring having a least one resilient arm extending from the spring base longitudinally and outwardly of the blade in a slot formed by adjacent fingers, a contact segment disposed longitudinally of the blade and within said slot, the free ends of this segment being disposed within and retained by the opposed recesses of the whirl and casing members, the spring arm being in engagement with this segment at a point intermediate the ends of the latter and remote from the base of the spring, and means providing a substantially fixed fulcrum point for that end of the contact segment which is disposed in the annular recess.

75 4. Apparatus of the character described comprising a blade, whirl and casing members mounted thereon and having opposed recesses therein, one of these members having its recess annular in form and spaced from the blade, fingers on the other of these members and extending into the annular recess and in firm engagement with the outer wall thereof, a spring comprising a substantially annular base portion disposed within the annular recess in firm engagement with a plurality of the fingers and with the inner wall of this recess for locking such fingers and the spring from relative circumferential movement, the annular base of the spring having a normal diameter slightly different from its diameter when assembled so that this base portion may yieldably en-

gage and be retained on one of the members which it engages when assembled for facilitating assembly, circumferentially spaced spring arms on the base of the spring and extending longitudinally and outwardly of the blade in slots formed by adjacent fingers for engagement with contact segments, a contact segment disposed longitudinally of the blade and within each of these slots, the free ends of each segment being disposed within and retained by the opposed recesses of the whirl and casing members, the spring arms being in engagement with the respective segments at points intermediate the ends thereof and remote from the base of the spring, and means providing substantially fixed fulcrum points for those ends of the contact segments which are disposed in the annular recess adjacent the base of the spring.

5. Apparatus of the character described comprising a blade, whirl and casing members mounted thereon and having opposed recesses therein, one of these members having its recess annular in form and spaced from the blade, this annular recess increasing in diameter from the base toward the open side thereof so that its outer wall is inclined to provide clearance for movement of contact segments, fingers on the other of these members and extending into the annular recess in firm engagement with the inclined outer wall thereof, a spring comprising a substantially annular base portion disposed within the annular recess in firm engagement with a plurality of the fingers and with the inner wall of this recess for locking such fingers and the spring from relative circumferential movement, circumferentially spaced spring arms on the base of the spring and extending longitudinally and outwardly of the blade in slots formed by adjacent fingers for engagement with contact segments, a contact segment disposed longitudinally of the blade and within each of these slots, the free ends of each segment being disposed within and retained by the opposed recesses of the whirl and casing members, the spring arms being in engagement with the respective segments at points intermediate the ends thereof and remote from the base of the spring so that these arms may be relatively long and flexible, the ends of the contact segments which are disposed in the annular recess being substantially in abutment with the base of the latter and fitting snugly between the inclined outer wall of this recess and the base of the spring, whereby the contact segments may rock about these ends as substantially fixed fulcrum points.

Signed by me at Whitinsville, Massachusetts this 21st day of July, 1928.

GEORGE H. MAGRATH.
